GEOMETRICAL INSTRUMENT

Joseph H. D. Beaucage, Pittsfield, Mass.

Application December 11, 1941, Serial No. 422,568

3 Claims. (Cl. 33—93)

This invention relates to improvements in geometrical instruments of the type used for inscribing angles accurately and speedily, more particularly to a geometrical instrument of simple construction which can be used with the maximum of accuracy and speed in various kinds of work for plotting angles.

Still another aim of the invention is to provide an instrument by which angles of any desired degree can be quickly and easily plotted by means of which the legs of the angle may be measured accurately when laid out to desired length.

Other objects and advantages of the invention will hereinafter become more fully apparent from the following description of the drawings, which illustrate preferred embodiments thereof, and wherein:

Figure 1 is a plan view of one form of the geometrical instrument,

Figure 2 is a fragmentary plan view of the bottom or reverse side thereof,

Figure 3 is a fragmentary sectional view taken substantially along the plane of the line 3—3 in Figure 1,

Figure 4 is a top plan view of another form of the instrument,

Figure 5 is a fragmentary bottom plan view of the same,

Figure 6 is a fragmentary sectional view taken substantially along the plane of the line 6—6 in Figure 4,

Figure 7 is a top plan view of still another form of the geometrical instrument,

Figure 8 is a fragmentary bottom plan view of the same, and

Figure 9 is a fragmentary sectional view taken substantially along the plane of the line 9—9 of Figure 7.

Referring more particularly to the drawings, wherein like reference characters designate like or corresponding parts throughout the different views, and referring particularly to Figures 1 to 3, 10 designates generally a geometrical instrument including a carpenter's square 11 to which is attached a member 12. The member 12 is in the shape of a quarter or quadrant of a circle. The member 12 is attached to one side of the carpenter's square 11 and at the apex thereof in any suitable manner, not shown, as by means of cement, brazing, welding or by suitable fastenings. The member 12 extends into the angle formed by the arms 13 of the square 11 and its curved edge 14 extends between said arms and partly overlap them. The upper, or exposed side of the member 12 is provided with degree mark-

ings and calibrations for indicating angles, preferably, at 15°, 30°, 45°, 60°, 75° and 90°, and which can be measured in either direction, as seen at 15. It will be noted that the member 12 is slightly larger than the quadrant of a circle in order that the two end calibrations can be spaced from the straight edges 16 of the member 12 and said calibrations are disposed over the arms 13 and are spaced outwardly from the inner longitudinal edges 17 thereof and are disposed substantially parallel to both the inner and outer longitudinal edges of the arms 13. A plurality of elongated blades or ruler arms 18 are attached to the under side of the member 12, in any suitable manner, and project radially from its edge 14 with said arms being arranged so that their longitudinal axes form continuation of the calibrations indicating angles of 15°, 30°, 45°, 60° and 75°. Obviously, the angles indicated by the calibrations 15 could be varied and the number of blades 18 and their relative positions could be correspondingly varied. As seen in Figure 1, the upper faces of the blades or ruler arms 18 are inscribed in inches and fractions thereof, beginning beyond the edge 14, and the inner edges 17 are correspondingly inscribed, while the outer longitudinal edges of the square arms 13 are marked in inches and fractions thereof, from the apex of said outer edges. The member 12 is preferably provided with a screw 19 which extends upwardly therethrough and to which is threadedly connected a knob 20, which is disposed on the upper side of the member 12 and which forms a handle for the instrument 10.

The end calibrations 15 are spaced from the edges 16 a distance equal to the distances between the longitudinal edges of the blades 18 and the calibrations 15, which are disposed intermediate of said edges. Consequently, an angle, for example, of 15° can be accurately plotted by drawing a line along one of the edges 17 and the longitudinal edge which is remote thereto of the blade 18, which is adjacent to said aforementioned edge 17. Likewise, angles of 15°, 30°, and so on, can be plotted by drawing lines along corresponding edges of the different blades 18. Likewise, it will be readily obvious that by providing linear scales on the arms 13 and blades 18 that the legs of the angles plotted can be accurately measured to desired lengths. The linear scales of the edges 17 provide convenient rules for drawing lines to scale when the outer edges of the square 11 are next to a straight edge or a T-square.

Another embodiment of the geometrical instrument, designated generally 21, is illustrated

in Figures 4, 5 and 6. The instrument 21 includes a conventional protractor 22 having an integral base 23, along the straight edge thereof and provided with an outer, straight edge 24 and extended ends 25 having inner, substantially straight edges 26, disposed substantially parallel to the edge 24. Curved edge 27 of the protractor 22 is provided with conventional calibrations and degree markings on the upper side of the protractor 22 and adjacent the edge 27. As best seen in Figures 5 and 6, a segment shaped supporting member 28 is swingably connected to the under or back side of the protractor 22 by means of a pivot pin or rivet 29. The supporting member 28 is provided with an upwardly offset, arcuately shaped edge portion 30 which is disposed in substantially the same plane as the upper side of the protractor 22 and the inner edge of which is in sliding engagement with the edge 27. Said upper surface of the portion 30 is provided with calibrations and degree markings which cooperate with the calibrations and degree markings of the protractor 22 to form a vernier scale, as seen in Figure 4. A pair of arms 31 are suitably attached, at corresponding ends thereof, to the under side of the supporting member 28 and project radially therefrom and are disposed at right angles to one another. A plurality of blades 32 are similarly attached, at corresponding ends thereof, to the under side of the member 28 and project radially therefrom and are disposed between the arms 31 and are equally spaced from one another. The blades or arms 32 correspond to blades 18 and are similarly arranged relatively to each other, preferably at angles of 15° apart and can be employed with the arms 31, in the same manner as previously described, with reference to the instrument 10, for plotting angles. Likewise, the upper sides of the blades 32 are inscribed with linear scale markings, similar to the blades 18, and the arms 31 are inscribed in the same manner.

The rivet 29 is disposed in the center of the curved edge 27 and at the center of the arcuately shaped offset portion 30 so that the member 28 can swing relatively to the protractor 22. The protractor 22 is provided with an arcuately shaped slot 33 and a screw or bolt 34 extends upwardly through the member 28 and loosely through the slot 33. The screw 34 carries a thumb nut 35 and a washer 36 preferably disposed between the thumb nut and the upper side of the protractor 22. It will thus be obvious that the member 28 can be swung relatively to the protractor 22 to position the arms 31 and 32 at various angles, as desired, after which the member 28 can be clamped to the protractor by tightening thumb nut 35. The ends of the portion 30 are adapted to abut against the edges 26 to form stops for limiting the swinging movement of the member 28 and when one of said ends is disposed in engagement with its edge 26 the longitudinal edges of the arm 31, adjacent thereto, will be disposed parallel to the straight edge 24. The zero calibrations of the protractor 22 are disposed parallel to the straight edge 24 so that said edge 24 can be employed with the arms 31 or blades 32 for measuring any angle from zero to one hundred eighty degrees, quickly and accurately. As seen in Figure 6, the underside of the base 23 extends to below the underside of the protractor 22 and is disposed in substantially the same plane as the undersides of the arms 31 and 32.

Another form of geometrical instrument, designated generally 37, is illustrated in Figures 7, 8 and 9 and includes a carpenter's square 38 having linear scale markings, corresponding to the carpenter's square 11. A substantially segment shaped member 39 is disposed on the square 38 and at the apex thereof and is suitably secured to an angular spacing strip 40 which, in turn, is suitably secured to the upper side of the square 38 for elevating the segments 39 above the surface of the upper side of the square 38. The length of the curved edge of the member 39, which is disposed in the angle formed by the arms of the square 38, is greater than an arc of 90° and the upper side of the member 39, along its curved edge, is calibrated and provided with degree markings from zero to ninety degrees, as indicated at 41. The zero and 90° calibrations are spaced inwardly from the arms of the square 38 and are adapted to be disposed parallel to the longitudinal edges thereof. A supporting member 42, as best seen in Figure 8, which corresponds to the member 28, is pivotally connected to the underside of the segment 39 by means of a rivet 43. The rivet 43 is disposed at the center of the curved edges of the members 39 and 42. The member 42 is provided with an upwardly offset portion 44, corresponding to portion 30 and which slidably engages the curved edge of the segment 39 and which is provided with a vernier scale for cooperation with the degree markings and calibrations 41. Six blades 45 are suitably secured, at corresponding ends thereof, to the underside of the member 42 and project radially from its curved edge. The blades 45 are spaced fifteen degrees apart and are provided on their upper sides with linear scales, corresponding to the blades 18. The segment 39 is provided with an arcuately shaped slot 46, as indicated in dotted lines in Figure 7, to receive a bolt 47 which carries a thumb nut 48 and washer 49, arranged in the same manner and for the same purpose as the bolt 34, nut 35 and washer 36. The length of the portion 44 is substantially fifteen degrees less than that of the exposed portion of the curved edge of the segment 39 so that the blades 45 can be swung to an arc of at least fifteen degrees to enable the instrument 37 to be adjusted for measuring any angle from zero to ninety degrees.

The operation and use of the instrument 37 is identical with that of the instrument 10 except that the blades 45 can be adjusted to lay out any angle up to ninety degrees, and a further description of the use of instrument 37 is therefore deemed unnecessary.

Various modifications and changes in the embodiment of the invention as disclosed, are contemplated and may obviously be resorted to, provided they fall within the spirit and scope of the invention as hereinafter defined by the appended claims, as only a preferred embodiment has been disclosed.

I claim as my invention:

65 1. A geometrical instrument comprising a segmental member having a curved edge extending more than 90 degrees and straight edge portions secured to the arms of a carpenter's square, a plate disposed below and pivoted to said segmental member to move in the angle of such a square, said plate having a curved portion concentric with said curved edge to coact therewith in protractor relation, and blade means extending from said portion.

70 2. A geometrical instrument comprising a seg-

mental member having a curved edge extending more than 90 degrees and straight edge portions secured to the arms of a carpenter's square, a plate disposed below and pivoted to said segmental member to move in the angle of such a square, said plate having a curved portion concentric with said curved edge to coact therewith in protractor relation, blade means extending from said portion, the ends of said plate being disposed for abutment against the arms of the carpenter's square to limit movement in opposite directions.

3. A geometrical instrument comprising a segmental member having a curved edge extending more than 90 degrees and straight edge portions

secured to the arms of a carpenter's square, a plate disposed below and pivoted to said segmental member to move in the angle of such a square, said plate having a curved portion concentric with said curved edge to coact therewith in protractor relation, blade means extending from said portion, the ends of said plate being disposed for abutment against the arms of the carpenter's square to limit movement in opposite directions, said plate portion being raised into approximately the plane of the segmental member, and the plate portion and segmental member at said curved edges having coacting calibrations.
